ELECTRICAL CIRCUIT DIAGRAM

John William Radford, Thayer, Ill., assignor of
one-half to Dewayne Radford, Springfield, Ill.

Application July 2, 1941, Serial No. 400,822

3 Claims. (Cl. 315—322)

My invention relates to means for selectively, conveniently and operatively controlling the flow of electric current in electric machines and especially in motion picture machines; an object being to provide a control circuit for such picture machines as will permit the successful use of but one rectifier or generator unit possessing the same amperage output as has heretofore required the service of two of such units.

(a) The object of my electric current shifting control circuit is to get the same results from a single rectifier or motor-generator, of same amperage, instead of using two rectifier units or motor-generators of the same amperage output.

(b) I attain these objects by using the electric current shifting control circuit illustrated in the accompanying drawing, as follows:

The single figure is an illustration of an electrical control circuit for this invention, and with it, an illustration of essential electrical and mechanical control members operatively connected therewith.

The figure in the drawing is an illustration of a circuit diagram in cooperative connection with means for its selective control.

I shall now describe my invention as I point out the essential features of novelty in the same.

In my invention I use for motion picture service a pair of projecting lamps 17 and 18, connectable to a single rectifier or generator member 16 by switches 8 and 1 respectively and projecting the picture to a screen (not shown) through openings 15 and 13 respectively; while an alternate use of lamps 17 and 18 will permit one lamp to be warmed up while the other is on an operating load just long enough ahead of the load transfer to let the warmed up lamp be ready for the sudden load shock without a weakening effect on the lamp and a possible disturbance of the light. Thus in the figure lamp 18 has the load, with switch 5 connecting resistance 4 with resistance 2 into the circuit between rectifier 16 and lamp 18 through switch 1; but before lamp 18 was given the full load switch 1 was used as a warming up switch, using only resistance 2 for this warming up of lamp 18. In like manner lamp 17 will be warmed up before a full load use by first throwing switch 8, using resistance 9 in the circuit between rectifier 16 and lamp 17, following which the closing of switch 12 will put the full load on lamp 17 using both resistance 9 and 11 for it; and permitting switch 1 to be pulled releasing lamp 18 until the warming up time for another load shift.

The operation of this invention is as follows:

By using a 30 ampere rectifier or generator, switch is closed, current flows through resistance 19, when change-over contact 5—switch 20 is closed, making two complete paths of 10 amperes each, or 20 amperes at arc 18. The current flow, producing 20 amperes at arc 18 is as follows: It flows through resistance unit 2 and out at resistance wire 3 connects resistances 2 and 19 to double throw switch 1; while wire 10 connects resistances 9 and 19 to switch 8, through resistance unit 4 and out at resistance unit 3, by switch 1 and contact 5, switch 20 being closed. Contact 12, switch 20 is open. Now 20 amperes arc light is projected through opening 13 to screen, because dowser 6 is open and dowser 7 is closed. Switch 8 is open. The change-over takes place from arc 18 to arc 17, as follows:

Switch 8 is closed, creating 10 amperes at arc 17, current flows in resistance path 9 and out at resistance path 10. Now twenty amperes is necessary at arc 17, for projection. Switch rod 14 is pushed to right causing dowser 6 to cover opening 13 and dowser 7 opens opening 15, contact 5 of switch 20 is open, contact 12 of switch 20 is closed adding 10 amperes more or a total of 20 amperes instantaneously at arc 17. The current flowing through contact 12 switch 20 in resistance path 11 and out at resistance path 10 back through switch 8 to arc 17. Switch 1 is opened, arc 18 is out, but 20 amperes is still maintained at arc 17, until change-over takes place again at arc 18. Then switch 1 is closed creating 10 amperes at arc 18. To receive 10 more amperes at arc 18 or a total of 20 amperes necessary for projection at change-over, push switch rod to left again. This completes operation.

Thus it will be obvious that both resistance units for each lamp will need to be of equal resistance value in order to permit a free and balanced flow of current through them and back through the center tap between them; providing a uniform and balanced resistance for the lamp circuit when the two resistance units are thrown in for a full load on a projection lamp.

Under the past and present set-up in motion picture theatres, for instance to supply 20 amperes for each arc, two 20 ampere rectifiers are necessary or one 20 ampere rectifier for each individual arc. If a motor-generator is used for arc supply, 40 amperes output is necessary to maintain 20 amperes at each arc. Note the savings by using this "electrical circuit."

1. Instead of using two rectifiers, as is neces-

sary under the present set-up, only one is necessary by using this "electrical circuit." That is saving 100% in initial or installation expense. Without this "electrical circuit" it is impossible to maintain two 20 ampere arcs from a single 30 ampere rectifier or generator.

2. When using a generator under the present set-up 40 ampere output is necessary to supply 20 amperes for each individual arc. As only one 20 ampere arc is in operation, except when change-over is made and both 20 ampere arcs are lit for but a short interval there is considerable power waste because it takes more power to supply a 40 ampere generator than a 30 ampere generator.

By using this "electrical circuit" with a generator, a 30 ampere generator will give the same results as a 40 ampere generator, without this "electrical circuit." Note the savings in initial or installation costs of generator by using this "electrical circuit." And also savings in operating expense.

I claim:

1. As a new electric circuit for motion picture projectors which are connected through a rectifying means with a source of electric energy, a pair of projection arc lamps, a lamp circuit for each lamp, a pair of spaced switches, a pair of spaced circuit terminals for said switches, a light shutter for each of said lamps, a common support for the shutters and said switches providing for their simultaneous operation, a pair of electrical resistance units connected serially into the circuit with each of said arc lamps, and with both units of each pair alike in resistance value and each pair connected in parallel through a double pole single throw switch with said arc lamps, and a center tap connection taken off the wire connection between said resistance units of each pair, each lamp circuit having a direct connection from said center tap to its corresponding projection arc lamp, the remaining terminals of the resistance set being respectively connected to said spaced circuit terminals, and a connection between the projection arc lamps and the power source of the rectifier controlled by said double pole single throw switch, the two sets of projection arc lamp circuits being connected in parallel electrically off the power source through the rectifier, thus permitting one of said projection lamps to be struck on relatively low amperage resistance while the other is operating at a higher level of resistance and both are securing their current from a power source through a generator.

2. As a new electric circuit for motion picture projectors which are connected through a generator with a source of electric energy, a pair of projection arc lamps, a lamp circuit for each lamp, a pair of spaced switches, a pair of spaced

circuit terminals for said switches, a light shutter for each of said lamps, a common support for the shutters and said switches providing for their simultaneous operation, a pair of electrical resistance units connected serially into the circuit with each of said arc lamps, and with both units of each pair alike in resistance value and each pair connected in parallel through a double pole single throw switch with said arc lamps, and a center tap connection taken off the wire connection between said resistance units of each pair, each lamp circuit having a direct connection from said center tap to its corresponding projection arc lamp, the remaining terminals of the resistance set being respectively connected to said spaced circuit terminals, and a connection between the projection arc lamps and a power source of the generator controlled by said double pole single throw switch, the two sets of projection arc lamp circuits being connected in parallel electrically off the power source through the generator, thus permitting one of said projection lamps to be struck on relatively low amperage resistance while the other is operating at a higher level of resistance and both are securing their current from a power source through a generator.

3. As a new electric circuit for motion picture projectors which are connected through a mercury arc with a source of electric energy, a pair of projection arc lamps, a lamp circuit for each lamp, a pair of spaced switches, a pair of spaced circuit terminals for said switches, a light shutter for each of said lamps, a common support for the shutters and said switches providing for their simultaneous operation, a pair of electrical resistance units connected serially into the circuit with each of said arc lamps, and with both units of each pair alike in resistance value and each pair connected in parallel through a double pole single throw switch with said arc lamps, and a center tap connection taken off the wire connection between said resistance units of each pair, each lamp circuit having a direct connection from said center tap to its corresponding projection arc lamp, the remaining terminals of the resistance set being respectively connected to said spaced circuit terminals, and a connection between the projection arc lamps and the power source of the rectifier controlled by said double pole single throw switch, the two sets of projection arc lamp circuits being connected in parallel electrically off the power source through the rectifier, thus permitting one of said projection lamps to be struck on relatively low amperage resistance while the other is operating at a higher level of resistance and both are securing their current from a power source through the rectifier.
